UNITED STATES PATENT OFFICE.

ROBERT HOLT, OF PATERSON, NEW JERSEY, ASSIGNOR TO R. & H. ADAMS,
OF SAME PLACE.

MACHINE FOR STRETCHING WOVEN FABRICS.

SPECIFICATION forming part of Letters Patent No. 230,703, dated August 3, 1880.

Application filed December 21, 1878.

To all whom it may concern:

Be it known that I, ROBERT HOLT, of Paterson, in the county of Passaic and State of New Jersey, have invented, certain Improvements 5 in Machines for Stretching Woven Fabrics, of which the following is a specification.

My invention relates to that class of machines for stretching and winding or rolling fabrics in which the edges of the fabric are 10 carried each between a belt and the face or periphery of a roll divergent from the line in which the fabric moves; and the improvements consist in the combination, with the stretching devices, of a free vibratory reel having its 15 ribs arranged eccentrically around its axis; in the construction of the ribs of the reel; and in the combination, with the stretching devices and reel, of a heating and pressing drum, to act upon the fabric while the latter is being 20 laid upon the winding-roll.

In the accompanying drawings, Figure 1 represents a front elevation of my improved machine; Fig. 2, a top-plan view of one end of the same; Fig. 3, an end elevation of the 25 same, having one of the stretcher-supports partially broken away to expose the internal driving-gear; Fig. 4, a vertical cross-section of the machine on the line $x-x$ of Fig. 1; and Fig. 5, a perspective view of the reel by which 30 the fabric is supported in passing through the machine.

The machine consists, essentially, of two divergent wheels or rolls and belts or bands traveling upon and partially around the same, 35 standards or supports for said wheels or rolls capable of being adjusted longitudinally upon the supporting bed or frame, a vibrating reel to support the fabric between the diverging wheels, a winding-roll, and a heating and 40 pressing drum, together with actuating mechanism for the various parts.

Referring to the drawings, A represents a bed or base frame formed or provided with overhanging longitudinal ribs or ways a , beneath or against which engage inwardly-extending flanges formed upon the under side of two supporting blocks or plates, b , located respectively at or near the opposite ends of the bed or base frame A, and capable of adjustment longitudinally thereon. Supported upon

each block of plate b is a hollow base or support, B, having at its bottom an outwardly-projecting flange or lip, over which engage a series of clips, c , as shown in Figs. 1, 2, and 3, this arrangement permitting the horizontal 55 rotation of the supports B when necessary, or the clamping of the same in any desired position; and bolted or otherwise secured upon the top of each base or support B is a bent or overhanging arm or standard, C. (Shown 60 more clearly in Fig. 1.) Each arm or standard C carries at its outer extremity a yoke, F, furnished at both its ends with a belt-pulley or roller, and supported in the arm or standard by means of a vertical screw rod or stem, z , 65 passing upward through the latter, and furnished at the upper side of the arm with a nut-wheel, z' , by which it may be adjusted vertically.

D represent two large wheels, which are 70 covered on their peripheries with rubber or equivalent material capable of taking firm hold upon the edge of the fabric. Each wheel D is secured upon a short horizontal shaft, B' , provided with a bevel-pinion, d , and supported 75 in suitable bearings upon the top of the base or support B at one end of the machine, as shown in Fig. 1, and receives a rotary motion through the gearing or meshing of the bevel-wheel d with a correspondingly-formed pinion, d' , secured upon a vertical shaft, which extends 80 upward through the hollow base B and receives motion from the driving-power, as hereinafter explained.

E represent two belts, of rubber or like 85 material, one of which passes over the upper side of each of the wheels D, and is thence carried outward beneath rollers or pulleys e , held and turning in outwardly-projecting arms formed upon or secured to the bases or supports B, and thence upward and over the rollers or pulleys of the yoke F, as shown in Figs. 3 and 4. Under the above arrangement the belts are caused to travel in contact with the upper faces of the respective wheels D, and to 90 press against the same with a greater or less force, which may be regulated by turning the wheel-nut z' , and thereby raising or lowering the yoke F.

From the above it will be seen that all the 100

parts of the machine directly connected with the wheels D and their belts E are mounted upon the supporting-bases B, and that the wheels derive their motion from vertical shafts 5 concentric with said bases. It therefore follows that the bases may be rotated upon their supporting-blocks b to change the divergence of the belt-wheels and belts; or the blocks b, with the bases and attendant parts supported 10 thereon, may be moved longitudinally upon the base or bed A to vary the distance between them without in any way interfering with the gearing or the position of the parts sustained by the bases B.

15 I, Figs. 1, 2, and 5, represents a reel which extends in a horizontal position between the belt-wheels D, and consists of a central shaft, x, and a series of longitudinal ribs, i, supported by radial arms extending from the shaft, 20 as shown.

As will be more clearly seen by referring to Figs. 4 and 5, the radial arms which project from hubs or bosses on the shaft x are of different lengths, those which support the first 25 or front rib being shortest and the others increasing regularly in length to the end of the series, thus causing the ribs i to be arranged eccentrically around the shaft or axis. By reference to Figs. 1 and 5 it will also be observed that the first or forward rib is curved 30 outward, and that the succeeding ribs gradually return to a straight form.

The shaft x of the reel is journaled at its ends in uprights or standards k, which are adjustable longitudinally of the bed A, upon which they are secured in the same manner as the blocks b, in order that they may be set to receive reels of different lengths, corresponding 35 with the distance between the stretching-40 wheels, which is in turn regulated by the width of the fabric and the amount of stretching desired.

The reel I is free to rock or vibrate to a limited extent in its bearings, and is prevented 45 by an upright, j, from rocking beyond the desired point.

The eccentricity of the reel, the curvature of its ribs, and its rocking or vibration facilitate the passage of the fabric and produce a 50 much more satisfactory result than the ordinary arrangement.

For the purpose of winding or rolling the fabric, I mount in the rear of the machine a horizontal roll, w, which receives the fabric from the rear side of the stretching-wheels and belts; and in order that the fabric may be wound smoothly and compactly and simultaneously dried, I mount below and parallel 55 with the roll w a hollow drum, H, which is provided at one end with a hollow trunnion, s, for the admission of steam or hot air to its interior for the purpose of heating the drum.

It will be observed by reference to Figs. 3 and 4 that the winding-roll is mounted in slot-65 ed standards, and that its entire weight rests directly upon the heating-roll, so that the fabric, while in a stretched condition and during

the instant that it is being laid upon the roll, is subjected to the joint action of heat and pressure, and thus laid smoothly and firmly in 70 place.

I am aware that a heating drum or roll to act upon the fabric leaving a stretching-machine is not new; but a peculiarity of my arrangement is that the winding-roll and the 75 heating-roll are arranged in such relation to each other and to the machine that the fabric is subjected to pressure as it is laid upon the winding-roll and while extended both laterally and longitudinally, thus insuring the placing 80 of the fabric in a smooth and compact shape upon the roll.

In operating the machine, the fabric passes inward between two parallel horizontal rods, m n, arranged one above the other, as shown 85 in Figs. 1 and 4, thence over the reel I, with its edges between the stretching-wheels and belts, and finally between the roll w and drum H, and around the former.

The rods m n are either or both of them furnished with collars l, capable of being adjusted lengthwise of the rods and clamped at any desired points thereon, their office being to guide the fabric, the width of which they are adjusted to correspond with.

The machine being constructed as above described, motion is communicated to its various parts from a driving-shaft, h', located at the rear side of the machine, by means of the gearing and belts represented in Figs. 1, 3, and 4, and which I will now explain. The driving-shaft h' is furnished, near one end, with a pinion, o, meshing with an idler-pinion, q, which, in turn, meshes with and gives motion to a cog-wheel, r, upon the shaft of drum H, thus 105 rotating the drum; and said driving-shaft h' is further provided at its middle with two conical pulleys, h, arranged with their bases toward each other. These pulleys h communicate motion through belts to two independent step or cone pulleys, g, mounted upon independent shafts g', located in opposite ends of the bed or base frame A. Each shaft g' carries a bevel-pinion, f', which meshes with and drives a horizontal bevel-wheel, f, secured upon 110 the lower end of the vertical shaft, which passes upward through the center of the base or support B and carries at its upper end the pinion d', through which motion is imparted to the large belt-wheels D, as above stated. The 115 pinions f' are adjustable lengthwise of their shafts, in order that they may be placed and kept in gear with the wheels f under the various adjustments of the bases B and their attendant parts.

It will be seen that under the above construction each stretching-wheel is driven independently of the other, and that by shifting the driving-belts upon the cone-pulleys either stretching-wheel may be caused to run faster 120 or slower than the other, the effect of which is to stretch the fabric more or less at one side or edge than at the other.

The eccentricity of the reel may be produced

either by varying the length of its radial arms, as shown, or by varying the width of the ribs or blades.

I am aware that the use of reels to support the fabric in connection with diverging stretching-wheels is old, and I lay no claim, broadly, thereto.

My improvements consist in so arranging the reel that it is allowed a limited rocking or vibrating motion on its axis independent of the stretching-wheels, in arranging the slats of a vibratory reel eccentrically around the axis, and in giving the ribs forms changing from curved to straight.

15 By permitting the vibration it is found in practice that the fabric, which is sometimes full in the center and at other times or at other points full on the edge, is subjected to a more even and uniform strain and delivered in a 20 smoother and better condition, and that this is greatly facilitated by the eccentricity of the reel and its tendency to turn forward, and by the peculiar form of the slats and their positions in relation to each other.

25 One or more of the ribs or blades of the reel may be curved outward, as desired.

Having thus described my invention, what I claim is—

1. In combination with the stretching-wheels and belts and their actuating mechanism, the 30 free vibratory reel having its ribs disposed eccentrically around the axis, substantially as described.

2. In a fabric-stretching machine, a rocking or vibrating reel having ribs on the receiving side curved longitudinally outward and the ribs on the delivery side straight, or approximately so, as shown and set forth.

3. In an organized machine for stretching, winding, and pressing fabrics, the combination 40 of divergent stretching-wheels, belts acting thereon, an intermediate sustaining-reel, a heating and pressing drum arranged to act upon the fabric while the latter is upon the roll, and actuating mechanism, substantially 45 as described.

The above specification of my said invention signed and witnessed at Paterson, New Jersey, this 14th day of December, A. D. 1878.

ROBERT HOLT.
